WHEEL DRESSER

William H. Koch, Evansville, Ind., assignor to
 Indian Archery & Toy Corporation, Evansville,
 Ind., a corporation of Indiana

Application October 15, 1949, Serial No. 121,596

6 Claims. (Cl. 125—11)

1

This invention relates to wheel dressing tools, and has particular but not limited reference to tools for the dressing of grinding wheels as used in connection with small, power operated hand tools.

The great majority of tools of this type have heretofore been of considerable bulk or extremely small, in either of which event the tool is awkward and hard to handle or control, while simultaneously controlling the power tool and associated grinding wheel. The present dressing tool, while not being of great size is so proportioned and constructed that it is very easy to handle while simultaneously providing a rest or support for the power tool. By such means, the relative positions of the dressing tool and the grinding wheel are easily controlled and regulated by the operator.

Thus, the object of the invention is to simplify the construction as well as the means and mode of operation of tools as disclosed herein, whereby such tools may not only be economically manufactured, but will be more efficient and accurate in use, adaptable to a wide variety of grinding tools, having relatively few parts and be unlikely to get out of repair.

It is a further object of the invention to provide such a tool which by reason of its relatively small size, simplicity and less costly construction may be easily acquired and used by individual power tool owners.

Another object of the invention is to enable wheel dressing by use of a small, hand held tool in which the pressure of the dressing element is under the continuous control of the operator.

A further object of the invention is to provide a mounting for the dressing element whereby it is securely held against dislodgment, yet is readily accessible for removal.

Still another object of the invention is to prolong the useful life of the dressing element by providing the element with a plurality of selectively or successively usable cutting edges.

A still further object of the invention is to utilize a cube-shaped dressing element to obtain a plurality of selectively or successively usable cutting edges, a further object in this connection being to utilize the cube-like shape of the dressing element to obtain a secure mounting therefor.

A further object of the invention is to provide in a tool of the character described means for supporting the power tool to thereby maintain the relative positions of the power and dressing tools within predetermined limits.

A further object of the invention is to provide a tool possessing the advantageous structural features, the inherent meritorious characteristics and the mode of operation herein mentioned.

With the above primary and other incidental objects in view as will more fully appear in the specification, the invention intended to be pro-

2

ected by Letters Patent consists of the features of construction, the parts and combinations thereof, and the mode of operation, as herein-after described or illustrated in the accompanying drawings, or their equivalents.

Referring to the accompanying drawing, wherein is found the preferred but obviously not necessarily the only form of embodiment of the invention,

10 Fig. 1 is a top plan view of a dressing tool in accordance with the instant invention;

Fig. 2 is a side view of the tool;

Fig. 3 is a view similar to Fig. 2, the tool being shown in longitudinal section;

15 Fig. 4 is a front end view of the tool;

Fig. 5 is a view in cross section, taken substantially along the line 5—5 of Fig. 1;

Fig. 6 is a detail view, in top plan, of the dressing element carrying slide; and

20 Fig. 7 is a fragmentary perspective view of the top of the dressing element carrying slide with the dressing element removed.

Fig. 8 is a fragmentary view, in perspective, of the tool, showing one manner of use thereof.

25 Like parts are indicated by similar characters of reference throughout the several views.

Referring to the drawings, according to the illustrative embodiment of the invention, a wheel dressing tool comprises an elongated bar-like body 10 presenting at one end thereof a notch 11 with tapering sides and a rounded bottom. In the region of the notch 11, the body 10 has a lesser thickness than over the remainder of its length. In the portion of greater thickness, one side of the body is channeled and undercut to define a longitudinal slideway 12 which at its one end opens onto the portion of lesser thickness.

30 Mounted in the slideway 12 is a slide 13, formed in a manner complementary to the slideway and having a short groove 14 in its underside. A screw 15 is passed from the underside of the body 10 into the slideway 12 and projects into the groove 14. The screw 15 accordingly acts as an abutment, defining limits of reciprocable motion for the slide 13.

35 The upper or left hand end of the slide 13 is formed with an enlarged head portion 16 in which is formed a recess or socket 17 opening through the outer end of the head 16. In a transverse direction it opens through the top side only of the head, there being defined at the bottom of the recess a land 18. The configuration of the recess is such as to receive a cube-shaped dressing element 19, permitting an edge of the element to protrude toward the notch 11.

40 The head 16 is provided with transversely projecting marginal flanges 20 disposed on the side of the head opposite the land 18. Such flanges are slightly longer than the head 16 extending therebeyond to provide a pair of inturned prongs

21 which overlie the dressing element 19. Thus, the recess 17 is of frusto-cubical shape, the frustum occurring at a point to define the inturned prongs 21 which prevent outward motion of the element.

The dressing element 19 is inserted in the recess 17 from the topside of the head 16 and seats upon the land 18 in complementary engaging relationship with the side walls of the recess and with the prongs 21. Withdrawal of the element through the top of the recess is normally prevented by a retaining plate 22 fastened to the body of the slide 13 and to the head 16 thereof by respective screws 23 and 24. The plate 22 is of such length as to project in partly overlying relation to the recess 17 and therefore to the element 19 when it is in place within the recess.

As shown in Fig. 1, the construction and arrangement of parts is such as to place the dressing element 19 in line with the notch 11, the protruding edge of the element lying in a plane at right angles to the longitudinal axis of the body 10. Further, the element is shiftable, by reason of the mounting of the slide 13, toward and from the notch 11. Referring to Fig. 8, in the use of the tool, the notch 11 presents a means to guide and position a spindle 25 which is held at right angles to the tool. The grinding wheel 26 on the end of the spindle then lies in parallel, adjacent relationship to the body 10 in an overlying position with respect to the cutting edge of element 19. The body 10 and its associated parts are adapted to be held in the hand of the operator who uses his thumb to advance the dressing element 19 into contact with the wheel, such motion being of course accompanied by rotation of the wheel to effect the desired dressing thereof. The retainer plate 22 and head 16 present a suitable abutment against which the operator may press to urge the dressing element against the wheel.

The dressing element 19 is made of a hard material suitable for its function, for example Norbide. By reason of its cubic shape, the element presents twelve usable cutting edges. When one edge becomes worn, retainer plate 22 is removed, the dressing element 19 is lifted from recess 17, turned to a new position of adjustment and reinserted in the recess, the retainer plate being then replaced.

From the above description it will be apparent that there is thus provided a device of the character described possessing the particular features of advantage before enumerated as desirable, but which obviously is susceptible of modification in its form, proportions, detail construction and arrangement of parts without departing from the principle involved or sacrificing any of its advantages.

While in order to comply with the statute the invention has been described in language more or less specific as to structural features, it is to be understood that the invention is not limited to the specific features shown, but that the means and construction herein disclosed comprise but one of several modes of putting the invention into effect.

Having thus described my invention, I claim:

1. A tool for wheel dressing, including a rectangular bar to be held in the hand and having a guide notch at one end thereof, a longitudinal slideway formed in one side of said bar, a slide in said slideway reciprocable toward and from said notch, an enlarged head portion at 75

the end thereof adjacent said notch, an angular recess in said head portion, a dressing element received in said recess and formed with a protruding cutting edge underlying said notch in a longitudinal sense, and a retainer plate removably fastened to said slide and partly overlying said dressing element, said retainer plate and said enlarged head presenting an abutment for the finger operation of said slide to urge said dressing element toward said notch.

2. A tool according to claim 1, characterized in that said dressing element is formed as a cube with each edge thereof representing a selectively usable cutting edge, the retainer plate being removed and the dressing element being readjusted to present a new cutting edge as each previously used edge becomes worn.

3. A tool for wheel dressing, including a rectangular body to be held in the hand, a notch at one end thereof to receive and position a wheel spindle in angular relation thereto, a support for a dressing element mounted on said body for limited sliding motion toward and from said notch, said support being manipulative by 20 the fingers of the operator, a cube-shaped dressing element carried by said support in a position underlying said notch in a longitudinal sense, the edges of said cutting element representing cutting surfaces, and a dressing element retainer plate on said support and removable therefrom to allow adjusting said element relatively to said support for successive use of the several edges of said element.

4. A tool according to claim 3, characterized in that said last named means includes a mounting for said dressing element utilizing the cube shape of said element for a secure gripping thereof.

5. A tool for wheel dressing, including a rectangular body to be held in the hand and presenting at one end thereof a locating notch to receive and position a spindle and associated wheel in operative relation thereto, a slide mounted on the body for reciprocatory motion longitudinally of the body under hand control, a lamination on the side of said slide adjacent one end thereof presenting a socket frusto-cubical in shape, and a cube-shaped dressing element received in said socket with one edge thereof protruding from the socket and beyond the end of said slide, in line with said notch, said slide being movable relative to said body toward said notch under influence of pressure applied by a finger or thumb of the hand.

6. A tool according to claim 5, characterized by a retainer mounted on the side of said slide in overlying relation to said socket, said retainer being removable for readjustment of said dressing element to bring the twelve edges thereof successively into protruding position.

WILLIAM H. KOCH.
